Inventor
Charles W. Mortimer

UNITED STATES PATENT OFFICE.

CHARLES W. MORTIMER, OF UPPER MONTCLAIR, NEW JERSEY, ASSIGNOR TO THE BARRETT COMPANY, A CORPORATION OF NEW JERSEY.

METHOD OF CUTTING SHINGLES.

Application filed November 1, 1924. Serial No. 747,305.

This invention relates to a shingle, the method of cutting the same from a sheet of roofing material and applying the same on a roof. It relates more particularly to shingles of the sort that are made from so-called felt base that is saturated with bituminous material such as asphalt, then coated with a layer of plastic bituminous material such as asphalt, and may have a coating of crushed mineral such as stone, slate, etc., applied thereto.

The shingles are cut from a sheet of roofing material in such a manner that they will have a wide rectangular upper portion and a somewhat pointed lower portion and are cut from the sheet so that there will be very little waste material. The shingles are installed with the narrow end downwardly and with the rectangular portions spaced a considerable distance apart.

The invention will be understood from the description in connection with the accompanying drawings, in which

Fig. 1 is a plan view showing the shingles applied to a roof;

Fig. 2 is a plan view showing how the shingles are cut from the sheet of roofing material.

As shown in Fig. 2 the shingles are cut so as to have a wide upper portion defined by the lines 1, 2 and 3 and a lower, somewhat pointed portion, defined by the lines 4, 5 and 6, and the sheet from which the shingles are cut is so laid out that two reversely turned adjacent shingles are cut longitudinally of the sheet and the pointed portions are adjacent to pointed portions of similar shingles on each side that are cut out in the same manner. In this way rectangular shingles are also cut out at intervals which will serve as the ordinary well known shingles. One of these rectangular portions is defined by the lines 3, 7, 8, 9 and 10. The only waste of material that occurs will be along the edges of the sheet as shown, for example, by the cut out portion to the right of the line 9 in Fig. 2.

The shingles are installed upon a roof as shown in Fig. 1 so that the narrow portions extend downwardly and the edges 1 and 3 of adjacent shingles are spaced apart a distance equal to the width of the narrowest portion or the length of the line 5. The narrowest portion of the shingle may for

example, be made one-half as wide as the widest portion. The next course is installed in a similar manner with the lower ends of their narrow portions at the lower ends of the edges 1 and 3 and bridging the space therebetween and so on for successive portions. It will thus be seen that the lower end 5 of a shingle in one course overlaps the upper edge 2 of a shingle in the second course below. In order to hold down the lower ends of the shingles to prevent them from curling up, suitable holders not shown but well known to those skilled in the art, may be used if desired. The exposed portions of individual shingles constitute six-sided figures or hexagons, these hexagons being contiguous and covering the surface of the roof. The shingles may be fastened to the roof as they are being installed by driving nails through the same near the corners as indicated at 11.

I claim:

1. The process of cutting shingles from a sheet of roofing material which comprises cutting staggered pairs of parallel lines longitudinally of said sheet, cutting transverse lines at the ends of said first named lines and joining the ends of said first named lines by cutting along diagonal lines.

2. The process of cutting shingles from a sheet of roofing material which comprises cutting staggered pairs of parallel lines longitudinally of said sheet, cutting staggered transverse lines at the ends of said first named lines and joining the ends of said first named lines by cutting along diagonal lines.

3. The process of cutting shingles from a sheet of roofing material which comprises cutting staggered pairs of parallel lines longitudinally of said sheet, cutting transverse lines at the ends of said first named lines, cutting transverse lines joining the middle points of lines of the respective pairs, and joining the ends of said first named lines by cutting along diagonal lines.

4. The process of cutting shingles from a sheet of roofing material which comprises cutting out rectangles in staggered positions, cutting along diagonal lines joining the corners of adjacent rectangles and cutting the portions thereby left into equal parts.

In testimony whereof I affix my signature.

CHARLES W. MORTIMER.
